CLAIM

The ornamental design for a gas cooktop as shown and described.

DESCRIPTION

CROSS-REFERENCE TO RELATED APPLICATION

This application claims the priority benefit of China Application Serial No. 202030201113.4, filed on May 7, 2020. The entirety of the above-mentioned patent application is hereby incorporated by reference herein and made a part of this specification.

FIGURE DESCRIPTION

FIG. 1 is a perspective view of a gas cooktop showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

The broken lines illustrate portions of the gas cooktop that form no part of the claimed design.
